(57) **CLAIM**

The ornamental design for a housing for a force sensor that measures the weight of vehicles that pass the sensor on the road, as shown and described.

DESCRIPTION

FIG. 1 is an elevated perspective view of an embodiment of the ornamental design for a housing for a force sensor that measures the weight of vehicles that pass the sensor on the road;

FIG. 2 is an enlarged perspective view of the housing of FIG. 1 taken from the front or the back section thereof;

FIG. 3 is a top plan view of the housing of FIG. 1 with the redundant middle portion omitted;

FIG. 4 is a bottom plan view of the housing of FIG. 1 with the redundant middle portion omitted;

FIG. 5 is a plan view of the front of the housing of FIG. 1, the back view being identical thereof;

FIG. 6 is a plan view of the left side of the housing of FIG. 1 with the redundant middle portion omitted; and,

FIG. 7 is a plan view of the right side of FIG. 1 with the redundant middle portion omitted.
